VIBRATOR WITH CRADLE

Henry S. Clark, Indianapolis, Ind., assignor, by
mesne assignments, to Cornell-Dubilier Elec-
tric Corporation, South Plainfield, N. J., a cor-
poration of Delaware

Application April 14, 1948, Serial No. 20,938

5 Claims. (CL 200—90)

1

The present invention relates to improvements in vibrating circuit interrupters of the type wherein a vibrating reed carrying suitable contacts oscillates, or vibrates, between relatively stationarily mounted contacts disposed on opposite sides of the reed. The reed itself is preferably driven by an electromagnet.

In structures of this character the reed vibrates at an extremely rapid rate varying from 60 times per second to multiples thereof.

As a result the apparatus as a whole is extremely sensitive and delicate and when under certain circumstances the structure as a whole is mounted within a containing case or is subject to pressure the amplitude of the reed may be seriously affected, thereby affecting the operation of the device.

It is one of the objects of the present invention to provide a means for so protecting the vibrator that there is no danger of the vibrator as a whole or the frame or base on which the parts are mounted being cramped in any way, or at least in such a manner to affect the operation of the device.

For the purpose of disclosing the invention I have illustrated certain embodiments thereof in the accompanying drawings in which:

Fig. 1 is a plan of a vibrator interrupter embodying my invention mounted within a container or casing and

Fig. 2 is a side elevation of the structure illustrated in Fig. 1 with a portion of the casing cut away.

Fig. 3 is a section taken along line 3—3 of Fig. 2.

Referring to the structure illustrated the vibrator comprises a frame having two side members 1 and 2 connected together with their top by a U-shaped connection bar 3. Assembled within this frame is a vibrating reed 4 carrying at its free end an armature 5 and supporting contact carrying arms 6 disposed on opposite sides of the reed and carrying contacts 7. These contacts are adapted to engage alternately contacts 8 mounted on spring fingers 9, disposed on opposite sides of the reed, and these spring fingers or contact carrying arms operate between pairs of rigid members 10 and 11. In its movement in one direction a contact on the reed 4 engages a stationary contact member for controlling the circuit of the driving electromagnet. The driving electromagnet 13 is supported from the U-shaped cross-bar 3 in a position with its pole piece 14 off-set relatively to the armature 5.

The reed 4, the contact arms 9, and the rigid arms 10 and 11 are all clamped in position in a

stack mounted at the bottom end of the frame. This stack comprises a plurality of separating plates between which the arms 9 and rigid members 10 and 11 are clamped at their bottom ends and those of the separating member adjacent the rigid arms 10 and 11 are formed of insulating material to insulate the contact carrying arms or fingers 9 from the remaining parts. Suitable clamping bolts extend through the stack, being suitably insulated from the current carrying parts. The structure therefore, is such that the stack portion of the interrupter is a substantially rigid structure.

Heretofore in commercial practice it has been found that the cramping of the frame comprising the side members 1 and 2 and the top member 3, especially at the non-stack end of the frame, will affect the correct operation of the interrupter.

This vibrator interrupter is generally enclosed in a suitable casing 15, preferably of sheet metal, provided with a removable cover 16, on which the contact prongs 17 of the vibrator are mounted. These prongs are suitably connected with the driving magnet 13, the vibrator reed and the relatively stationary contact arms 9 by suitable electrical conductors (not shown).

The casing 15 is generally provided with a sponge rubber lining 18 adapted to cushion the vibrator interrupter and at the same time dampen the noise of the reed when in operation.

It frequently occurs that when the vibrator reed is nested within the casing it may be placed in position slightly cocked or during the handling thereof the interrupter as a whole may be slightly cocked, which results in pressure being exerted on the side members 1 and 2 or on the end member 3. This has a tendency to affect the operation of the vibrating reed and of the vibrator as a whole resulting in the improper operation of this structure. To prevent any such cramping of the vibrator frame I provided what may be called a stirrup member on each side of the frame. Each of these stirrup members or spacers comprises a pair of side arms 19 and 20 suitably spaced apart and connected together at their bottom ends by a cross-piece 21. This cross-piece is clamped to the frame by suitable clamping screws 22 which will be noted pass through the stack and therefore, clamp the protecting or side members with the rigid portion of the frame. The side protecting members 19 and 20 diverge from the rigid piece so that they are spaced apart from the frame members 1 and 2 and are of sufficient

length to extend beyond the end of the vibrator interrupter frame.

The protecting members 19 and 20 may be of spring material so that the vibrator interrupter unit may have a certain amount of vibratory movement between the same.

By this arrangement it is to be noted that the vibrating unit is nested in the sponge rubber lining of the casing and is protected against any pressure on its sides except at the point of the stack which of course is a rigid structure.

I claim as my invention:

1. An electromagnetic vibrator interrupter comprising a frame, an electromagnetic coil mounted at one end thereof, a vibratory reed clamped at the opposite end thereof and having its free end extending toward said coil, contact carrying arms disposed on opposite sides of said vibratory reed and clamped to said frame with said reed, spacer members for said reed and contact arms comprising a stack at the lower end of said frame and resilient spacer arms secured at the stack end of said frame, projecting beyond the side edges of said frame, extending longitudinally of said frame and diverging from said frame toward their free ends.

2. An electromagnetic vibrator interrupter comprising a frame, an electromagnetic coil mounted at one end thereof, a vibratory reed clamped at the opposite end of said frame and having its free end extending toward said coil, contact arms disposed on opposite sides of said vibratory reed and clamped at said opposite end of said frame with said reed, spacer members between said reed and arms forming a relatively rigid stack at said opposite end of said frame, and resilient spacer arms clamped to said frame at said stack end, extending beyond the side edges of said frame, diverging longitudinally of the frame and extending beyond the electromagnetic coil end of the frame.

3. An electromagnetic interrupter comprising a frame, an electromagnetic coil mounted at one end thereof, a vibratory reed clamped at the opposite end thereof and having its free end extending toward said coil, contact arms disposed on opposite sides of said vibratory reed and clamped to said frame at said opposite end thereof, spacer members disposed between said arms, said reed and said frame, and forming a rigid stack at said opposite end of said frame and resilient spacer arms secured to the stack end of

said frame extending longitudinally of said frame to a point beyond the coil end of the frame and beyond the opposite edges of said frame, said spacer members diverging from the sides of the frame toward the coil end.

4. An electromagnetic vibrator interrupter comprising a frame, an electromagnetic coil mounted at one end thereof, a vibratory reed clamped at the opposite end thereof, and having its free end extending toward said coil, contact carrying arms disposed on opposite sides of said vibratory reed and clamped to said frame with said reed, spacer members disposed between said contact arms, said reed, and said frame and forming a rigid stack at said opposite end of said frame at the stack end thereof and spacer members extending longitudinally of the frame, said spacer members each comprising a U-shaped member, the base of the U being clamped to the frame and the legs of the U being resilient and extending longitudinally of the frame to a point beyond the coil end of the frame and extending beyond the side edges of the frame, said U-shaped arms diverging from the stack end of the frame.

5. An electromagnetic vibrating interrupter, comprising a frame, an electromagnetic coil mounted at one end thereof and having its free end extending toward said coil, contact arms disposed on opposite sides of said vibratory reed and clamped to said frame with said reed, spacer members disposed between said arms, reed, and frame at said opposite end of said frame and forming a rigid stack, a pair of relatively resilient spacer arms disposed on the opposite sides of said frame, clamped to said frame at the stack end thereof, diverging outwardly from said frame and extending beyond the end of said frame and an enclosing casing for said interrupter having a resilient lining, the resiliency of said spacer arms being less than the resiliency of said lining.
